DEVICES FOR USE IN SEPARATING THREADS

Nellie Ancona Feld, 100 Avenue P,

Brooklyn, N.Y. 11204

Filed Dec. 9, 1966, Ser. No. 600,432

10 Claims. (Cl. 57—2.3)

This invention relates to devices for use in separating one or more threads or strands from a larger number thereof, which are twisted together, held together or are stuck together to form a single bundle of threads.

In needlework, such as embroidery, petit point, gros point or crewel work, an operator is usually provided with a bundle comprising a number of threads or strands of cotton or wool which are together coextensively. These threads may be stuck together or twisted together and the operator or user has to separate one or more threads from the rest. This operation has been difficult. An object of this invention, therefore, is to provide a device of the character described to aid in or facilitate separating one or more threads from the rest of the threads in the bundle of threads. With this device one end of the bundle of threads is wedged unto a hook of a weighted device. The operator then separates the desired number of threads from the rest of the threads in the bundle at the opposite end, holding the selected threads between fingers of one hand and the rest of the threads gripped by fingers of the other hand. The hands are then moved apart to pull the selected threads from the rest of the threads. During such movement the weighted device will rotate to untwist the bundle and facilitate the separation of the threads. At the end of the untwisting operation, the threads are pulled off the weighted device.

A further object of this invention is to provide a weighted device of the character described provided with a spring hook provided with a wedging groove into which the lower end of the bundle of threads may be easily but tightly wedged.

Another object of this invention is to provide a device of the character described, comprising a box. The box comprises a bottom case filled with weighted material and into which the base of the hook is embedded, with the hook projecting above said case.

Yet another object of this invention is to provide a device of the character described, a cover hinged to said case which when closed covers the hooking end of the hook.

A further object of this invention is to provide a device of the character described, in which a weighted piece of metal is embedded in the material which fills the case.

A still further object of this invention is to provide a device of the character described, in which the case and its cover may be opened up to a position where the case and cover are in horizontal alignment so that the cover aids in swinging the weighted device during the untwisting of the yarn.

Still another object of this invention is to provide a strong, rugged and durable device of the character described which shall be inexpensive to manufacture, safe and easy to use, and which shall yet be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of invention will be indicated in the following claims.

In the accompanying drawing, in which is shown an 70 illustrative embodiment of this invention,

FIG. 1 is a perspective view showing the weighted

2

device in operation during the untwisting movement of a bundle of threads;

FIG. 2 is an end elevational view of said device; and

FIG. 3 is a side view of the device with parts broken away and in cross-section.

Referring now in detail to the drawing, 10 designates a weighted device embodying the invention which may be used as an aid in separating one or more strands, threads or pieces of yarn 11 from the remaining group of the threads 12 of a bundle of threads 13.

The threads in bundle 13 may be of wool or cotton or other suitable fibers and may be used in needlework such as embroidery, petit point, gros point or crewel work. The threads or yarn in the bundle 13 are coextensive and are often stuck together because the fibers of one strand interengage the fibers of other threads. Sometimes these strands are twisted together. The user or operator often has to separate one or more selected strands 11 from the rest of the strands 12 of the bundle 13.

Heretofore, this operation has been difficult and tedious.

The device 10 embodying the invention may be used as an aid to facilitate separating one or more strands 11 from the rest of the strands 12 from the bundle 13. The device 10 comprises a case 11a to which a cover 12a is hinged.

The case 11a may be made of rigid plastic and comprises a bottom wall 14 from which there extends upwardly a front wall 15 and a rear wall 16, interconnected by a pair of parallel side walls 17. The case 11a may be of square horizontal shape and may be made of plastic.

The front wall 15 has a top edge 15a, the rear wall 16 has a top edge 16a and the side walls 17 have top edges 17a. The edges 15a, 16a and 17a are in a common horizontal plane parallel to the bottom wall 14. Extending upwardly from the rear wall 16 and projecting above edge 16a is a hinge bracket 20 having concavely recessed ends 21. The hinge bracket 20 is located closer to one side wall 17 than to the other. Also extending upwardly from rear wall 16 and near the opposite side wall 17, are a pair of spaced brackets 22 each formed with a ball head 23.

The casing 11a and the cover 12a may be identical, hence the cover 12a has a top wall 14, a front wall 15, a rear wall 16 and side wall 17. The rear wall 16 of cover 12a has a hinge bracket 20 likewise formed with concavely recessed ends swingably receiving the ball heads 23 on the brackets 22 of the case 11a. Also integrally formed with the rear wall 16 of the cover 12a, are brackets 22 provided with ball heads 23 projecting into the concave ends of the bracket 20, on the rear wall 16 of the case 11a. The lower edges of the cover 12a contact the upper edges of the case 11a when the box is closed.

Means is provided to snap the box shut. To this end there is integrally formed with the front wall 15 of the case 11a adjacent the upper edge 15a, a forwardly projecting horizontal ledge or bracket 30 formed with an integrally upwardly and rearwardly inclined round pin 31 which projects above the edge 15a. The bracket 30 is located closer to one side wall 17 than to the other. The pin 31 is located forwardly of the front wall 15 as shown in FIG. 1 of the drawing. Front wall 15 is also formed with a pair of integral spaced semi-conical projections 32. The front wall 15 of the cover is formed with bracket 30, pin 31 and semi-conical projections 32. When the cover is snapped shut the pin 31 of the case will frictionally engage between the semi-conical projections 32 of the cover, whereas the pin 31 of the cover will engage between the semi-conical projections of the case.

The case 11a may be filled with a plastic filler 40 coming up to the level of the top edges 15a, 16a and 17a and forming a block. A metal weighted disc or other member 41 may be embedded in the plastic block 40 to add to the weight of the case.

A hook 42 is embedded in the plastic block 40. Said hook 42 may be made of flat metal spring wire and comprises a shank 43, which is substantially vertical and has its lower end extending down into the block 40, and it is provided with an offset or bent finger or foot 44 to better anchor the hook to the block 40. At its upper end, hook 42 has a downwardly bent, forwardly curved beard or hook portion 45 forming a wedging crevice 46 with the shank 43. The upper end of the hook 42 is of such height as to be disposed below the top wall 14 of the cover when the box is closed. The beard 45 projects forwardly toward the front walls 15. When the box is closed the cover 12 protects the hook from being damaged and prevents the hook from damaging or hurting anybody.

When the box is opened up to a position where the cover and case are horizontally aligned, the lower end of a bundle of threads 13 may be wedged into the wedge shaped crevice 46 between the beard 45 and the shank 43. The operator or user may then grasp the upper ends of the threads 11 between fingers of one hand, and the upper end of the remaining threads 12 may be grasped by fingers of the other hand. The two hands of the user may then slowly move apart to separate the threads 11 from the threads 12. During this operation the weight of the open box causes the bundle 13 to be held in vertical position and the opened up box rotates to permit untwisting of the bundle 13. During this operation the threads 11 form an angle with the threads 12 as shown in the drawing, and as the threads are pulled apart, more and more of the threads 11 become separated. When the separation reaches the hook 42, said threads may be pulled off the hook and pulled apart.

It will thus be seen that there is provided an apparatus and article in which the several objects of this invention are achieved, and which is well adapted to meet the conditions of practical use.

As possible embodiments might be made of the above invention, and as various changes might be made in the embodiment above set forth, it is to be understood that all matter herein set forth or shown in the accompanying drawings, is to be interpreted as illustrative and not in a limiting sense.

I claim:

1. A weighted device comprising a base, a hook mem-

ber of spring material, means to anchor the lower end of said member to said base, said member having an upper hook portion projecting upwardly above said base, and forming a wedging groove, and a cover on said base enclosing the upwardly projecting portion of said member.

5 2. The combination of claim 1, said base comprising a case, and said anchoring means comprising molded, weighted material in said case with said lower end of the hook member embedded in said material.

10 3. The combination of claim 2, said cover comprising a case hinged to said base case.

4. The combination of claim 2, said case and cover being identical.

15 5. The combination of claim 2, said base case having a bottom wall, side walls and front and rear walls, said cover comprising a cover case having a top wall, side walls and front and rear walls, with the lower edges of the side, front and rear walls of said cover contacting the upper edges of said side, front and rear walls, respectively, of said case, means to hinge the rear wall of the case to the rear wall of the cover, and means to latch the front wall of said case to the front wall of said cover.

20 6. The combination of claim 2, and a piece of metal embedded in said material to add weight to said case.

25 7. The combination of claim 5, said base case and cover case being made of transparent plastic.

8. The combination of claim 1, said hook member comprising flat metal wire.

25 9. The combination of claim 8, and said hook portion facing forwardly.

30 10. The combination of claim 1, said cover being hinged to said base and said base and cover having mutually interengaging latch means.
